O, SENDER.

DEVICE FOR TRUING GRINDING WHEELS.

APPLICATION FILED JUNE 10, 1920.

1,407,954.

Patented Feb. 28, 1922.

UNITED STATES PATENT OFFICE.

OTTO SENDER, OF SCHAFFHAUSEN, SWITZERLAND.

DEVICE FOR TRUING GRINDING WHEELS.

1,407,954.

Specification of Letters Patent. Patented Feb. 28, 1922.

Application filed June 10, 1920. Serial No. 387,984.

To all whom it may concern:

Be it known that I, OTTO SENDER, a citizen of the Republic of Switzerland, residing at Schaffhausen, Ringstrasse 6, Switzerland, have invented certain new and useful Improvements in a Device for Truing Grinding Wheels; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

This invention relates to improvements in a device for the truing of grinding wheels. Truing grinding wheels has been carried out up to the present by means of various tools and devices. Diamonds have been used for instance but they are best suited for the small emery-wheels of circular or surface grinding machines.

For truing larger sized emery-wheels such as are in use in work shops or foundries, the well known trimmers are used which consist of a holder carrying several small wheels of hardened steel. The latter are pressed against the quickly rotating emery-wheel in order to perform the truing. Such a tool presents the following disadvantages: At the very high speed with which these small wheels rotate they are subjected to rupture. The wear of these wheels is very great and also the spindles on which they are mounted and the bearing faces of these spindles wear out after a very short time of running.

Trimming hammers are further used for truing grinding wheels. They are fitted on both ends with chisel-like faces with which the emery-wheel is hewn until it runs true again. This is a very tedious work and if it is not performed by a very skilled man the danger always exists that an emery-wheel treated in this way will burst when being put to work again. The crumbling of the emery off the wheel edges and the formation of a ragged surface cannot be avoided when trimming an emery-wheel by means of such a hammer.

Furthermore known impact tools, driven from the grinding wheel shaft, operate on the wheel while running at the same speed as when grinding, which is detrimental to both tools and wheel.

According to the present invention using dressing tools of impact type, the wheel to be dressed is driven in accordance with the operation of the tools, so the wheel rotates but slowly as compared to other dressing methods.

By reason of the slow rotation of the wheel and rapid movement of the tools the dressing of the wheel can be completed in a single rotation, if the wheel does not deviate too much from a circle.

An exemplification of the invention is shown on the accompanying drawing, in which:

Fig. 1 is a plan view of the device;

Fig. 2 is a side view;

Fig. 3 is a front view;

Fig. 4 shows a detail, in front and side elevation;

Fig. 5 is a section along line V—V of Fig. 1;

Fig. 6 is a section along line VI—VI of Fig. 5, and

Fig. 7 is a general arrangement view of the device fitted to a grinding machine.

The foundation plate 25 of the device is fitted with two holes for bolts to pass through in order to fix the plate to the T rest of a grinding machine. Grooves 27 provided in the foundation plate 25 serve to take up a base plate 26 which is adjusted in these grooves so that the chisels 4 are at a distance of for instance 3 mm from the emery-wheel 23 when the distance piece 9 is inserted between the stroke limiting rings 8 and the casing 2 of the chisel rams. Then any further displacement of plate 26 is prevented by tightening nut 28. A rotation of approximately 90 revolutions per minute is imparted to the driving pulley 1 of the device and the distance piece 9 is removed.

The chisels work on the emery-wheel until the stroke limiting rings 8 of the chisel rams 3 bear against the casing 2. The emery-wheel is then sufficiently trimmed unless it was very much out of true. In the latter case the device, that is to say plate 26 is once more adjusted with regard to the working face of the emery-wheel in the manner described above and the chisels are set to work again.

The driving pulley 1 is mounted on the outer end of a driving shaft 10 which passes through all the ram casings 2. A toothed wheel 5 provided with six teeth shaped similar to those of a ratchet wheel is fixed

to shaft 10 in the vertical center-plane of each ram 3. The number of strokes of the rams is thus six times the number of revolutions of the driving shaft. As is shown in Fig. 1 in dotted lines the holes provided in the shaft 10 for the pins with which the wheels 5 are fixed to the shaft are staggered so that the rams do not strike the emery-wheel all at the same time but one after the other. Upon a turning of the shaft 10 the teeth of the wheels 5 push the rams 3 back and compress the cylindrical springs 7 by engaging in their turning motion with face 21 of a recess 24 provided in the ram, whereupon the rams are pushed forward towards the emery-wheel by the pressure of the cylindrical springs 7. The impact of the chisels against the surface of the emery-wheel has the effect that raised parts are removed from the emery-wheel so that the grinding face of the latter is smooth again.

A worm 17 is mounted on driving shaft 10 which engages a worm-wheel 18 mounted on shaft 12 to which rotation is thus imparted. On the working end of this shaft 12 a stirrup-like member 13 is mounted, which can carry out a turning motion around the axis of the shaft 12 that is limited by the action of stops 15 against a fixed rod 14. Between the shanks of the stirrup two friction wheels 29 are carried on a spindle 16, the circumference of these friction wheels is fitted with rubber tyres. These rubber tyres are pressed into circular grooves 30 provided on the shaft 12 whereby the rotary movement of the latter is transmitted to the friction rollers 29. Furthermore the rubber tyres are pressed against the lateral face of the emery-disc 23 by the torsional action of a cylindrical spring 31 on the stirrup 13, whereby the rotary movement of the friction rollers 29 causes the emery-wheel to rotate slowly. The rams 3 are slotted at their working end for the purpose of inserting chisel-plates therein and they are provided with clamping-screws to securely fix the inserted chisel plate in the slot. A hole 6 arranged transversely to the axis of the ram is provided in every ram-casing, into which a rod is inserted which engages with the flat surfaces of the recess 24 in the ram and prevents any turning motion of the latter about its axis. The shaft 12 can be shifted in an axial direction relatively to the worm-wheel, two further tapped holes are provided in the shaft 12 in which a set pin is screwed in in order to fix the worm-wheel in the new position on the shaft after the latter has been shifted. This arrangement enables obtaining a good working surface for the friction wheels nearer the center of the emery-wheel, if the outer lateral part of said wheel is much worn.

A number of individual impact tools used to build up one truing device may vary ac-

cording to the width of the emery-wheel to be trued. The rigidity of the truing device composed of a number of individual impact tools is attained, besides fixing them on the common base plate 26, by three bolts 20 passing through the impact tool casings and pressing them together between the bracket parts 11 and 19.

I claim:

1. A device for truing grinding wheels, comprising a number of mechanically operated individual impact tools, adjustable means to fix the device at a working distance from the face of the grinding wheel, driving means for operating the impact-tools independently from each other, and a friction device operated by said driving means for imparting a rotary feed movement to the grinding wheel. 75

2. A device for truing grinding wheels, comprising a number of mechanically operated individual impact-tools fitted with removable working edges, adjustable means to fix the device at a working distance from the face of the grinding wheel, driving 80 means for operating the impact-tools successively and independently from each other, and a friction device operated by said driving means for imparting a rotary feed movement to the grinding wheel. 85

3. A device for truing grinding wheels, comprising a number of individual impact tools each consisting of a spring loaded ram guided in a casing fitted with removable working edges, adjustable means to fix the 100 device at a working distance from the face of the grinding wheel, driving means for operating the spring-loaded rams successively and independently from each other, and a friction device operated by said driv- 105 ing means for imparting a rotary feed movement to the grinding wheel. 95

4. A device for truing grinding wheels, comprising a number of individual impact tools each consisting of a spring-loaded 110 ram guided in a casing and fitted with removable working edges, a common base plate to which the individual impact-tool casings are secured, a foundation plate fixed to a support and provided with guide 115 grooves in which said base plate can be adjusted and fixed so that the impact-tools are at a working distance from the face of the grinding wheel, driving means for operating the spring loaded rams successively 120 and independently from each other, and a friction device operated by said driving means for imparting a rotary feed move- 125 ment to the grinding wheel.

5. A device for truing grinding wheels, comprising a number of individual impact-tools each consisting of a spring-loaded ram guided in a casing and fitted with removable working edges, means to fix the device at a 130 working distance from the face of the grind-

ing wheel, a driving pulley to which rotation is imparted, a driving shaft passing through all the impact-tool casings to one end of which the driving pulley is fixed, 5 toothed wheels one of which is fixed to the driving shaft in each vertical center-plane of the rams, each wheel engaging with a recess provided in each ram so that upon the rotation of the toothed wheel the ram is 10 displaced in an axial direction whereby the spring is compressed and the ram is pushed towards the grinding wheel as soon as the tooth of the wheel comes out of engagement with the face of the recess, and a friction 15 device operated by the driving shaft for imparting a rotary feed movement to the grinding wheel.

6. A device for truing grinding wheels, comprising a number of individual impact- 20 tools each consisting of a spring-loaded ram guided in a casing and fitted with removable working edges, means to fix the device at a working distance from the face of the grinding wheel, a driving pulley to 25 which rotation is imparted, a driving shaft passing through all the impact-tool casings to one end of which the driving pulley is fixed, toothed wheels one of which is fixed to the driving shaft in each vertical cen- 30 ter plane of the rams, the wheels being mounted so that their teeth are angularly offset, each wheel engaging with a recess provided in each ram so that upon the ro-

tation of the toothed wheel the ram is displaced in an axial direction whereby the 35 spring is compressed and the ram is pushed towards the grinding wheel as soon as the tooth of the wheel comes out of engagement with the face of the recess, and a friction device operated by the driving shaft for 40 imparting a rotary feed movement to the grinding wheel, a worm mounted on the other end of the driving shaft, a worm-wheel engaging with said worm, a shaft to which said worm-wheel is fixed and thereby 45 rotation is imparted from the driving shaft, friction wheels rotated by said shaft and carried in a device adapted to swing on the shaft said friction wheels being resiliently pressed against the lateral surface of the 50 grinding wheel thereby imparting through the frictional action rotation to the grinding wheel.

7. In a grinding wheel dresser, a plurality of mechanically operated impact tools, a 55 driving shaft common to said tools, friction wheels for engaging the side of the grinding wheel to rotate it, mechanism to drive said wheel from said shaft, and means to permit the adjustment of said friction 60 wheels to and from the centre of the grinding wheel.

In testimony that I claim the foregoing as my invention, I have signed my name.

OTTO SENDER.
